UNITED STATES PATENT OFFICE.

CALEB R. BASINI, OF CARTERET, NEW JERSEY.

WINDOW SCAFFOLD.

Application filed October 7, 1922. Serial No. 593,109.

To all whom it may concern:

Be it known that I, CALEB R. BASINI, a citizen of the United States, and a resident of Carteret, in the county of Middlesex and State of New Jersey, have invented a new and Improved Window Scaffold, of which the following is a full, clear, and exact description.

This invention relates to scaffolds and particularly to an improved readily removable scaffold adapted for use in connection with windows.

Another object of the invention is to provide a scaffold particularly adapted for windows which may be set up and collapsed quickly and easily and readily adjusted to different size windows.

A further object of the invention is to provide a removable scaffold for windows which may be applied and removed without injuring the window or the scaffold.

In the accompanying drawings—

Figure 1 is a longitudinal vertical section through part of a window and through a scaffold embodying the invention.

Figure 2 is a perspective view of part of one end of the scaffold shown in Figure 1.

Figure 3 is a horizontal sectional view through a window showing in top plan the scaffold illustrated in Figure 1, the section being taken through Figure 1 approximately on line 3—3.

Figure 4 is an elevation of the scaffold when folded.

Referring to the accompanying drawings by numeral, 11 indicates the wall of a building and 12 the window frame, said frame being provided with the usual bottom jamb 13, said jamb being adapted to receive the horizontal supporting bars 14 and 15 which bars may be made of any desired material, as for instance, wood, said bars at one end being connected together by an adjustable connecting structure 16. The structure 16 is preferably made from two wood bars 17 and 18 cut away at 19 and 20 respectively whereby they may co-operate together as illustrated in Figure 3. An encircling strap 21 is secured to each of the bars 17 and 18 near their reduced ends so that these bars may be spread apart until the straps 21 engage and may be moved towards each other until the respective ends 22 and 23 engage the respective end sockets 24 and 25. Pref-

erably, a reinforcing strap 26 is secured in any desired manner to the large end of each of the bars 17 and 18, said strap and said bars being provided with a plurality of apertures 27 for receiving the respective screws or bolts 28 and 29, said screws or bolts extending into the horizontal bars 14 and 15 to connect the structure 16 thereto. The structure 16 acts as a stop bar for the horizontal bars 14 and 15 and rests against the window frame 12 when the device is in use as indicated in Figures 1 and 3.

Each of the bars 14 and 15 is provided with a vertical standard 30 and a diagonal brace 31 which are rigidly secured to the respective bars and are rigidly secured together at their lower ends by suitable fastening means, as for instance, screws 32. Preferably, the brace 31 extends a short distance beyond the standard 30 so as to engage the wall 11 while the upper part of the standard 30 is engaging the jamb 13 and the bars 14 and 15 are thereby held in a horizontal position. A suitable platform 33 may be mounted on the bars 14 and 15 loosely or may be secured thereto by bolts or any other suitable securing means. At the outer end of each of the horizontal bars 14 and 15 there is provided an upright 34 which is preferably formed of angle iron, said uprights being pivotally connected in place by a suitable pivotal bolt 35. A notch 36 is arranged in the upper end of the upright 34 co-acting with the notch 37 of the rail 38. It will be noted that the notch 37 is deeper than the notch 36 whereby the flange 39 of the rail will overlap notch 36 and thereby become locked to the upright 34.

The rail 38 is preferably divided into two sections 39 and 40, said sections being preferably angle irons and adjustably locked together by reason of the bolt 41 fitted into section 40 and extending through the slot 42 in the section 39. A link 43 is pivotally connected with the upright 34 near the top, said link having a hook end 44 at one end, 100 said hook end 44 interlocking with an eye screw 45 which is screwed into the window frame 12. It will be noted from Figure 3 that there are two eye screws 45 for supporting the respective links 43, which links in turn are pivotally connected with the respective uprights 34. The rail 38 connects these uprights whereby with this rail and

the links 43 a fence or railing is provided so that the workmen using the scaffold cannot readily fall off.

When it is desired to remove the scaffold, 5 the links 43 are disconnected from the screw eyes 45 and rail 38 is disconnected from the uprights 34. After this has been done, the uprights are folded as indicated in Figure 4 and the horizontal bars 14 and 15 are also 10 folded in a similar manner. The screw eyes 45 are left in place preferably so that in case it is desired to again use the scaffold on that particular window, they will be in position for use. The scaffold may be 15 quickly and easily set up and removed and, consequently, may be used for cleaning the windows or for painting the window frames and sashes. By reason of the slot 42 and the 20 adjustable feature of the structure 16, the device may be used in narrow windows or

wide windows. It will, of course, be evident that the boards forming the platform 33 must be of the desired width to rest on the bars 14 and 15 though ordinarily these boards are provided long enough to rest on 25 the bars 14 and 15 when the scaffold has been adjusted to its greatest width.

What I claim is:—

In a scaffold of the character described, a platform means for supporting the platform, a stop rail connected with said supporting means, said stop rail being formed in two sections, said sections having reduced overlapping portions, a pair of straps for guiding said overlapping portions, and telescoping angle bars connected to the opposite ends of said platform supporting means for preventing the spreading of the same. 30 35

CALEB R. BASINI.
